ENRICO GARDA, OF PARIS, FRANCE.

APPARATUS FOR TRANSFORMING LIQUIDS INTO A MIST.

Application filed February 24, 1923. Serial No. 621,104.

To all whom it may concern:

Be it known that I, ENRICO GARDA, of 68 Rue Reaumur, Paris, France, have invented Apparatus for Transforming Liquids into a 5 Mist, of which the following is a full, clear, and exact description.

The present invention has for its object an apparatus for transforming into a mist, by means of a compressed fluid, liquids of 10 any composition and density. This apparatus is essentially characterized by the fact that the fluid under pressure, compressed air for instance, adapted to drive the liquid to be pulverized through the apparatus, es- 15 capes from the latter through nozzles of any suitable shape and cross section for ensuring its distribution and its exit about the apparatus. This result is attained by im- 20 parting to the said fluid, successive impulses producing at the outlet of these nozzles, a vibratory and whirling field, composed of the liquid divided in multiple jets. As this liquid is thus driven outside the apparatus, it is violently projected, broken and trans- 25 formed into a mist the particles of which, owing to the friction to which they are sub- 30 jected, acquire an electric charge of the same sign, repel each other and create an im- palpable and dry mist which, according to the liquids employed, is applicable to medi- 35 cine, hygiene or industry.

The apparatus forming the subject-matter of the present invention is essentially con- 40 stituted by the combination:

(a) Of a central core so shaped as to pre- 45 sent, midway of its height, a cylindrical swelling above and below which respectively open apertures communicating the upper ones, with a compressed fluid inlet conduit, the lower ones with an inlet conduit for the liquid to be pulverized;

(b) Of a tubular body connected to the compressed fluid inlet conduit and enclosing the upper part of the central core on which 50 it is secured, this tubular body terminating at its base by a crown, resting on the upper face of the cylindrical swelling of the central core, and being provided with notches which form nozzles adapted to ensure the escape about the apparatus of the com- 55 pressed fluid conveyed by the conduit and the upper orifices of the central core into a chamber formed between the latter and the tubular body which covers it;

(c) Of a second tubular body connected, at its lower part, to the inlet conduit for the

liquid to be pulverized, and enclosing the lower part of the central core on which it is mounted so as to be capable of being moved longitudinally and adjusted in position, this 60 second tubular body being provided, on its upper edge, with an inner circular groove in which the swelling of the central core fits with a slight play so as to form a passage of adjustable cross section permitting the issue 65 of the liquid which, drawn by the fluid under pressure in a chamber formed between the central core and the second tubular body, is emulsified with the said compressed fluid which, at the same time, enters in combina- 70 tion with the liquid for forming an impalpable and dry mist.

In order that the invention may be clearly understood, a form of construction of the improved pulverizing apparatus will be de- 75 scribed hereafter with reference to the accompanying drawing in which:

Fig. 1 is a front elevation.

Fig. 2 is a vertical section.

Fig. 3 shows the central core in front ele- 80 vation.

Figs. 4 and 5 respectively illustrate in vertical section the upper and lower tubular bodies.

Fig. 6 is a perspective view of the index. 85

As illustrated in the accompanying drawing, the apparatus in accordance with the invention comprises a core which, turned off as shown in Fig. 3, is provided, midway of its height, with a cylindrical swelling or en- 90 largement 1 the opposite faces of which are respectively connected by conical surfaces to two cylindrical parts 2 and 3 perforated with orifices respectively opening into longitudinal channels 6 and 7 drilled in the axis 95 of the central core and which do not communicate together, as clearly shown in Fig. 3.

This core terminates, at its ends by two threaded parts 8 and 9 which are respectively adapted to receive by screwing the 100 upper tubular body 10 and the lower tubular body 11 which are respectively connected to the inlet pipe for a fluid under pressure, compressed air for instance, and to a vessel containing the liquid to be pulverized.

The upper body 10, which is shaped in such a manner as to enclose the upper part of the central core, fits with a slight friction on a cylindrical part 12 of the latter and terminates, at its base, in a crown resting on the upper face of the enlargement 1 of the said central core and provided, on

its periphery, with notches 13 adapted to form distinct nozzles permitting the regular escape all round and outside the apparatus, of the fluid under pressure (air or the like) 5 conveyed by the channel 6 and openings 4 into the circular chamber 14 formed at the base of the body 10.

The upper body 10 is also provided at its base with a flange 15 in which is formed a 10 circular groove 16 adapted, as will be explained, to create eddies in the product transformed into a mist.

The lower body 11 fits and is also guided with a slight friction on a cylindrical part 15 17 of the central core which it encloses, at its lower part, beyond which it is connected, by a suitable conduit, to a vessel containing the liquid to be transformed into a mist.

This tubular body 11 terminates at its 20 upper part by a crown 18 in which is formed a circular groove 19 adapted to form a housing for the cylindrical enlargement 1 of the central core.

This enlargement 1 fits in the groove 19 25 with a certain play which as clearly shown in Fig. 2 forms a passage permitting the escape to the exterior of the apparatus of the liquid to be pulverized, sucked, by the flow of the fluid under pressure through 30 the notches 13, into the chamber 20 formed in the body 11 and conveyed in the said chamber through the channel 7 and the openings 5 of the said central core.

From the foregoing it will be understood 35 that the fluid under pressure is subjected, during its passage through the notches 13, to a rolling which determines successive impulses of the said fluid and the creation at the outlet of the notches of a vibratory and 40 whirling field which produces the drawing along of the liquid film issuing from the groove 19 and that the said liquid film is drawn along, then violently projected outside the apparatus, the said film whirling in 45 the groove 16 and being broken into a mist the particles of which, owing to the energetic friction to which they are subjected, are charged with electricity of the same sign and repel each other forming an absolutely 50 impalpable and dry mist.

In order to allow of varying the proportions of the liquid drawn along by the escape of the compressed fluid, the lower tubular body 11 is mounted on the central core 55 so that it can be longitudinally displaced on the latter for adjusting at will the section of the passage formed between the enlargement 1 and the groove 19.

In the example shown, the tubular body 60 11 is provided with an inclined slide 21. A screw 22 is secured to the central core and extends through the slide 21, said screw being provided with a nut at 23 and an index 65 24, said index being loosely mounted upon the screw whereby the value of the angular

displacement of the tubular body 11 on the threaded part 9 may be determined and the latter placed at any desired position as indicated by a suitable graduation 25 of said tubular body. In order to prevent the rotation of the index upon the screw when the nut 23 is adjusted said index is provided with a boss 24^a, the flat sides of which engage the inclined walls of the slide 21. 70

The above described arrangements are, of course, given by way of example only, the forms, materials and dimensions of the constituent parts can be modified without departing thereby from the principle of the invention. 75

Claims.

1. An apparatus for transforming liquids into a mist, comprising a central core,—a cylindrical enlargement on the said core, means for bringing a fluid under pressure 85 above the enlargement,—means for bringing the liquid to be pulverized below the enlargement,—an upper tubular body mounted on the central core,—a chamber at the lower part of this tubular body,—a crown at the 90 base of the said tubular body and resting on the upper face of the enlargement,—notches in the said crown for permitting the issue of the compressed fluid all round the upper tubular body,—a lower tubular body mounted on the lower part of the central core,—a chamber at the upper part of this tubular body,—a circular groove formed in the upper edge of the said tubular body for receiving with a certain play the cylindrical 95 enlargement of the central core and forming a passage for the flow of the liquid to be pulverized,—means for adjusting the cross section of this passage. 100

2. An apparatus for transforming liquids 105 into a mist, comprising: a central core,—a cylindrical enlargement on the said core,—a longitudinal channel for the admission of the fluid under pressure, drilled in the axis of the core above the enlargement, openings 110 in the said core in communication with the lower portion of the channel,—a second longitudinal channel for the admission of the liquid to be pulverized, drilled in the axis of the core below the enlargement, openings 115 in this core in communication with the upper portion of the second channel,—a tubular body mounted on the central core, connected to the compressed fluid inlet and enclosing the portion of the core situated above the enlargement,—a chamber at the lower portion of the tubular body, surrounding the openings of the central core which are situated above the enlargement,—a 120 crown at the base of the said tubular body and resting on the upper face of the enlargement,—notches in the said crown for permitting the issue of the compressed fluid all round the upper tubular body,—a second tubular body connected to the inlet for the 125 130

liquid to be pulverized and enclosing the portion of the core situated below the enlargement,—a chamber at the upper part of this second body, surrounding the openings provided in the core and below its enlargement,—a circular groove formed in the upper edge of the said tubular body for receiving with a certain play the cylindrical enlargement of the central core and forming a passage for the flow of the liquid to be pulverized,—means for adjusting the cross section of this passage.

3. An apparatus for transforming liquids into a mist, comprising: a central core,—a cylindrical enlargement on the said core,—a longitudinal channel for the admission of the fluid under pressure, drilled in the axis of the core above the enlargement, openings in the said core in communication with the lower portion of the channel,—a second longitudinal channel for the admission of the liquid to be pulverized, drilled in the axis of the core below the enlargement, openings in this core in communication with the upper portion of the second channel,—a tubular body mounted on the central core, connected to the compressed fluid inlet and enclosing the portion of the core situated above the enlargement,—a chamber at the lower portion of the tubular body, surrounding the openings of the central core which are situated above the enlargement,—a crown at the base of the said tubular body and resting on the upper face of the enlargement,—notches in the said crown for permitting the issue of the compressed fluid all round the upper tubular body,—a second tubular body connected to the inlet for the liquid to be pulverized and enclosing the portion of the core situated below the enlargement,—a chamber at the upper part of this second body, surrounding the openings provided in the core and below its enlargement,—a circular groove formed in the upper edge of the said tubular body for receiving with a certain play the cylindrical enlargement of the central core and forming a passage for the flow of the liquid to be pulverized,—an inclined slide and a graduation on the second tubular body,—an index mounted on the fixed central core,—a clamping nut for immobilizing the second tubular body in any desired position on the central core.

The foregoing specification of my "apparatus for transforming liquids into a mist" signed by me this 6th day of February 1923.

ENRICO GARDA.
